UNITED STATES PATENT OFFICE.

CARL ROCHELLE, OF WASHINGTON, NORTH CAROLINA.

RAIL-LOCKING DEVICE.

1,255,465.

Specification of Letters Patent.

Patented Feb. 5, 1918.

Application filed November 23, 1916. Serial No. 133,070.

To all whom it may concern:

Be it known that I, CARL ROCHELLE, a citizen of the United States, and a resident of Washington, in the county of Beaufort 5 and State of North Carolina, have invented an Improvement in Rail-Locking Devices, of which the following is a specification.

My invention relates to an improvement in devices for locking the movable rails of 10 a switch so as to prevent the derailment of a train when the latter is passing a siding due to the crowding of the movable switch points out of their normal position.

An object of my invention is to provide a 15 device which will lock the movable switch points in position so as to prevent the movement of the switch points due to the jar which is transmitted to the operating lever of the switch stand thereby causing the lever to work upwardly and to move the switch point into such position as to cause the wheels of certain cars of the train to pass out on the siding when the switch is set in its normal position, *i. e.*, for permitting 20 a clear passage along the main line.

A further object of my invention is to provide spring means for positively holding the movable switch point close to the rail during the normal position of the switch 30 but which may be moved so as to permit the movement of the rails to permit a train to pass onto the siding.

A further object of my invention is to provide an auxiliary locking device to be 35 used in connection with the ordinary switch stand for accomplishing the objects named above.

My invention is illustrated in the accompanying drawings which form a part of 40 this application in which—

Figure 1 is a plan view of a portion of a railroad track equipped with my improved locking device.

Fig. 2 is a view similar to that shown in 45 Fig. 1, showing the parts moved to run the train onto a siding.

Fig. 3 is a section along the line 3—3 of Fig. 1.

Fig. 4 is a section along the line 4—4 of 50 Fig. 1.

Fig. 5 is a perspective view of one portion of the rail locking device.

Fig. 6 is a perspective view of another portion of the rail locking device.

55 In Fig. 1 the main track rails are shown

at 1 and 2, respectively. At 3 and 4 are the movable track rails for switching the car onto the siding. As is usual with this construction, the movable rails 3 and 4 are tapered at their ends and are arranged to engage the respective rails 1 and 2, being moved into and out of engagement by means of a switch bar 5 which is operated from a switch stand 6 by the ordinary mechanism not shown.

In Fig. 1 I have shown a supporting base 7 for each of the uprights 8 and 9, respectively. Pivotally mounted in the upright 8 is a locking member 10 whose end extends into a slot 9^a of the upright 9. In this slot 70 9^a is pivotally mounted a foot lever 11 upon which the end of the locking member 10 rests. Downward pressure on the outer end of the foot lever 11 tends to raise the locking member.

A locking bar 12 is provided which passes through a U-shaped bracket 13 secured to the rail 2, this arm 12 being pivotally secured to a bracket 14 which is in turn secured to the inner side of the movable switch point 4. The locking bar 12 has a pin 15 against which a spiral spring 16 bears, the other end of the spring bearing on the bracket 13.

From the foregoing description of the 85 various parts of the device the operation thereof may be readily understood. The switch stand 6, as has been explained before, is of the ordinary construction. Many times the jar of a train passing over a switch will cause the movable rails to vibrate so as to gradually work the switch lever (not shown) of the switch stand up to a position where it will cause the movable switch point to spread to an extent that will permit the 90 flanges of the wheels of the train to suddenly throw the switch point out of its normal position and thereby turn the wheels to the side track.

In the present instance, however, this cannot be done because in the position of the apparatus shown in Fig. 1, which is the normal position of the switch, the movable rail member 4 is held by means of the spring 16 into close contact with the main rail 2, 100 so that notwithstanding any vibration the movable rail member 4 will not be moved away from the main rail 2 far enough to permit the flange of the wheel to enter between the rail joint and the main rail 2. 110

Moreover, the locking member 10 has entered a slot 12^a in the locking bar 12 so as to hold the parts positively locked.

Now when it is desired to turn the switch 5 so as to permit a train to enter the siding the foot lever 11 is depressed thus raising the locking member 10 clear of the slot 12^a. The movable rail members 3 and 4 may now be moved by means of the switch rod 5 10 through the turning of the switch lever in the switch stand 6, against the tension of the spring 16. This position is illustrated in Fig. 2. When now the switch is set in its normal position the movement of the locking 15 bar 12 will cause the locking member 10 to again enter the slot 12^a, thus positively locking the rails in their normal position.

The device described above is designed to eliminate those accidents caused by the 20 slight movement of the movable rails during the passage of a train. Thus in the case where the switch has been inadvertently left in position to turn the cars onto a siding, if a train should come from the direction in 25 which the side track extends, that is to say in such a direction that the passage of the train on the main line would tend to "split the switch", the switch bar 5 will be broken under ordinary circumstances and the switch 30 points or ends of the movable rail members 3 and 4 will be left open so that when a train on the main line comes in the opposite direction it will be turned onto the siding.

With my invention should such a "splitting of the switch" occur the switch points would be forced to the normal position to open the main line and the locking bar 12 would cause the locking of the parts so that in the subsequent passage of a train in the 40 opposite direction it would proceed on the main line and not be turned off onto the siding. This would eliminate one of the many dangers which now exist due to the "splitting of the switch" and the leaving of the 45 line in condition to derail the train.

I claim:

1. The combination with a railroad track having main track rails, of movable rails for switching purposes arranged to be moved 50 into and out of engagement with said main track rails, a locking bar secured to one of said movable rails, a locking member arranged to engage said locking bar when said movable rail is in engagement with a main 55 rail, and means for disengaging said locking member from said locking bar at will.

2. In a switching system, a main track rail, a movable rail arranged to be brought 60 into and out of engagement with said main track rail, a rod pivotally secured to said

movable rail, an abutment carried by the rod, a spring disposed upon the rod, one end of the spring bearing against said abutment and the other end of the spring bearing against the stationary rail.

65

3. In a switching system, a main track rail, a movable rail arranged to be brought into and out of engagement with said main track rail, a rod pivotally secured to said movable rail, an abutment carried by the rod, a spring disposed upon the rod, one end of the spring bearing against said abutment and the other end of the spring bearing against the stationary rail, and gravity operated means for automatically locking the 75 rod in its normal position.

4. In a switching system, a main track rail, a movable rail arranged to be brought into and out of engagement with said main track rail, a rod pivotally secured to said movable 80 rail, an abutment carried by the rod, a spring disposed upon the rod, one end of the spring bearing against said abutment and the other end of the spring bearing against the stationary rail, gravity operated means for automatically locking the rod in its normal position, and a foot lever for raising said gravity operated means to release the locking rod.

5. In a switching system, a main track 90 rail, a movable rail arranged to be brought into and out of engagement with said main track rail, a rod secured to said movable rail and provided with a slot, an abutment carried by the rod, a spring disposed upon 95 the rod, one end of the spring bearing against said abutment and the other end of the spring bearing against the stationary rail, gravity operated means arranged to enter said slot for automatically operating 100 the rod in its normal position, and a foot lever for raising said gravity operated means to release the locking rod.

6. In a switching system, a main track rail, a movable rail arranged to be brought 105 into and out of engagement with said main track rail, a rod secured to said movable rail and provided with a slot, an abutment carried by the rod, a spring disposed upon the rod, one end of the spring bearing 110 against said abutment and the other end of the spring bearing against the stationary rail, a lever pivoted at one end and having a portion arranged to enter the notch in said rod when the latter is in its normal position 115 for locking the rod, and a foot lever for raising said locking lever to release the locking rod.

CARL ROCHELLE.
